E A

DE 11,557

NO. 11,557

DEC 30, 1879

UNITED STATES PATENT OFFICE.

EDWARD F. REED, OF MALDEN, ASSIGNOR TO NOVELTY RATTAN COMPANY,
OF DOVER, MASSACHUSETTS.

DESIGN FOR CHAIRS.

Specification forming part of Design No. **11,557**, dated December 30, 1879; application filed April 22, 1879.
[Term of patent 7 years.]

To all whom it may concern:

Be it known that I, EDWARD F. REED, of Malden, in the county of Middlesex and State of Massachusetts, have invented a new and original Design for Chairs, of which the following is a specification.

The nature of my design is fully shown in the accompanying photographic illustration, forming a part of this specification.

The feature of my design for chairs consists in the peculiar form given to the front legs, whereby, first, the grace and beauty of the chair are enhanced; and, second, the legs are enabled to be extended above the chair-seat, and be practically continuous with the arms of the chair when the chair is of the class known as "short-armed," so that the strength and durability of the connection of the legs and arms to the seat in a short-armed chair are greatly increased, all of which I will now proceed to describe.

In the photograph I have represented a short-armed rattan-chair, this being the class of chairs to which the peculiarly-formed legs constituting the chief feature of my design are particularly adapted, although they may be applied to willow or other chairs, and to chairs with long arms or without arms.

A represents the seat, which is of the usual or any suitable form. B B represent the front legs, which constitute the chief part of my design. Each of these legs is substantially straight from its lower end—say two-thirds (more or less) of the distance from the lower end to the seat—and terminates at its upper end in two curves, *s s'*, forming together an S-shaped or ogee curve, as shown, the curve *s* extending from the straight portion of the leg backwardly toward the rear of the chair, and the curve *s'* extending upwardly from the curve *s* into, through, or by the seat-frame. The legs are thus extended backwardly, so that they enter or are connected to the seat-frame considerably in the rear of the points where the straight portions of the legs would meet the seat if said portions were continued to the seat. The upwardly-extending curve *s'* enables the leg to enter the seat at about a right

angle with the latter, and separates the curve *s* from the seat, so that the effect produced is different from that of a leg curved backwardly and terminating in a portion parallel with the seat, and attached directly thereto. The upper ends of the curved portions *s'* enter sockets in the seat-frame, or are otherwise secured to the latter in any suitable manner.

The described curvature of the legs imparts a graceful and ornamental appearance to the chair, and enables the legs to form parts or continuations of the arms D D when the arms are of the usual length employed in short-armed chairs, and are formed and curved to extend upwardly from the seat and then backwardly to the back, as shown.

Heretofore in this class of chairs the legs have been connected to the seat at points in front of the arms, and have been supported by braces extending to the front and sides of the seat-frame. When the chair is rocked or tilted by its occupant there is a strain exerted on the back and seat, which tends to separate or detach both the arms and the legs from the seat, and materially damages the chair. By curving the front legs as described I bring their upper ends back, so that they may be continued up through or by the seat-frame and form continuations of the arms. The combined leg and arm thus formed may be in a single piece, or in two or more pieces suitably spliced or connected. The continuation of the curved legs and the short arms not only gives a graceful and pleasing effect, but also gives such a secure connection of the arms and legs to the seat that the arms cannot be separated from the seat, and the seat cannot be separated from the legs unless the material of the combined legs and arms is broken, all the tensile strength of said material being utilized to hold the seat, arms, and legs together. I do not limit myself, however, to the continuation of the legs and arms, as the curved legs may be disconnected from the arms or used in chairs without arms.

I have shown how the beauty of these rattan or willow chairs may be enhanced in the construction of the back, which is curved back-

wardly and provided at its opposite sides with medallions *m*, the peripheries of which form continuations of the curve of the back. Each medallion is provided with a central knob or projection, *m'*.

I claim—

1. The design for a chair in which each of the front legs terminates at its upper end in the curves *s s'*, forming together an S-shaped or ogee curve, the curve *s* extending backwardly toward the rear of the chair, and the curve *s'* extending upwardly to the seat-frame, substantially as shown.

2. The design for a short-armed chair in which each of the front legs terminates at

its upper end in the curves *s s'*, forming together an S-shaped or ogee curve, the curve *s* extending backwardly toward the rear of the chair, and the curve *s'* extending upwardly through or by the seat-frame and joining the vertical portion of one of the arms *D*, substantially as shown.

In testimony whereof I have signed my name to this specification, in the presence of two subscribing witnesses, this 12th day of April, 1879.

EDWARD F. REED.
